US00D932805S

(12) **United States Design Patent** (10) **Patent No.:** **US D932,805 S**
Chen (45) **Date of Patent:** **** Oct. 12, 2021**

(54) **CUSHION**

(71) Applicant: **HONGKONG FORTUNE
INDUSTRY TECHNOLOGY CO.,
LIMITED**, Kowloon (HK)

(72) Inventor: **Li Chen**, Kowloon (HK)

(**) Term: **15 Years**

(21) Appl. No.: **29/764,156**

(22) Filed: **Dec. 29, 2020**

(51) LOC (13) Cl. **06-09**

(52) U.S. Cl. **D6/601**
USPC ....

Primary Examiner — Sanjeev Paul

(57) **CLAIM**

The ornamental design for a cushion, as shown and described.

DESCRIPTION

FIG. 1 is a front perspective view of a cushion, showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
